(57) **CLAIM**

The ornamental design for a utility knife, as shown and described.

DESCRIPTION

FIG. 1 is a right-side elevational view of the invention with the blade extended and the grip depressed;

FIG. 2 is a left-side elevational view of the invention with the blade extended and the grip depressed;

FIG. 3 is a right-side elevational view of the invention with the blade retracted and the grip unactuated;

FIG. 4 is a left-side elevational view of the invention with the blade retracted and the grip unactuated;

FIG. 5 is a top view of the invention with the blade extended;

FIG. 6 is a perspective view from the rear end of the invention with the grip unactuated; and,

FIG. 7 is a perspective view from the rear end of the invention with the grip depressed and the blade extended.

The broken lines depict portions of the utility knife in which the design is embodied that are not considered part of the claimed design.
